JAMES COOK, OF HOHOKUS, AND PERCY COOK, OF DELAWANNA, NEW JERSEY.

FABRIC-FOLDING MACHINE.

Application filed May 10, 1927. Serial No. 190,209.

This invention relates to machines for creasing, folding, doubling or performing other substantially similar operations on fabrics or other flexible sheets while advancing the same edgewise, and particularly to that class of such machines in which some instrumentality received in a lengthwise doubling formed in the sheet serves to define the fold as the sheet progresses. The object 10 of the invention is to construct a machine of this character in which the direction of the line of fold may be controlled, especially with a view to preventing its failure to run true; in the example herein shown and described the control is automatically effected. The invention consists in the combination, 15 with supporting means and means therein coacting to keep the sheet taut while being advanced, one of which coacting means acts 20 to maintain the sheet spread to substantially its initial width and the other of which acts to maintain the sheet doubled with the apex of the doubling projecting from a plane coincident with the spread portion of the 25 sheet, of a fold-forming member, acting in effect like and which we therefore herein term a "rudder", revoluble in the supporting means back and forth on an axis penetrating said plane and having guiding contact with 30 the sheet within its doubled portion.

In the drawing,

Fig. 1 is a side elevation of a machine embodying the invention; and

Fig. 2 is a diagrammatic plan, showing 35 the mentioned coacting means and fold-forming member and certain automatic means for controlling the latter.

The first mentioned of the aforesaid coacting means includes, with a guide 1, as a 40 roller, a series of bars 2 around which zig-zag fashion the sheet A extends from a table 3 on which it is piled in folds as shown in Fig. 1; or instead of the bars there may be a suitably journaled beam 4 on which a roll 45 of the sheet is mounted. In each instance a drag is imposed on the sheet, so that it is tautened when pulled upon and thereby advanced, and the guide 1 serves to maintain the sheet spread to its initial width. There 50 may be a roller 5 around which the sheet extends and which thereby augments the tension in either case, and for sufficiently augmenting the tension in the second case there may be a guide bar 6 over which the sheet 55 extends in a bend. The guide 1 may be ar-

ranged at different elevations in an inclined set of bearings 7 in the main frame 8.

The other of said coacting means here includes a pair of members preferably in the form of bars 9. These are here parallel to each other and stand in the example vertically, being suitably mounted in the frame 8 forward of the guide 1. Said means also here includes rotary means 10 to wind up the folded sheet, such being arranged relatively forward of the bars 9 and here having its axis of rotation vertical. That one of said coacting means which is now being described obviously acts to maintain the sheet doubled. It is not material that this 60 means embody the elements shown and described; it is only material, in the broad aspect of the invention, that it maintain a doubling in the sheet with the apex of the doubling projecting from the plane which, as at guide 1, is coincident with the aforesaid spread portion of the sheet. Means 10 here comprises a head-stock 11 and a tail-stock 12 journaled in the frame, and a pair 65 of slats 13 on which the bolt B of the sheet is wound up, these being preferably pivoted at their lower ends in the head-stock and detachably interlocked at their upper ends in some way with the tail-stock so as to permit 70 their being swung outward on their pivots clear of the tail-stock in removing the wound bolt. The head-stock is preferably power-driven from a motor 16 through the belt- 75 and-pulley system 17 shown.

The fold-forming member or rudder, according to this invention, projects into the channel formed in the sheet by the doubling and in guiding contact with the sheet and is capable of oscillation on an axis penetrating the plane of the said spread portion of the 80 sheet. The purpose of its oscillatory motion is to utilize it, while it is forming the fold, in controlling the direction of the line of fold. In the present example this fold-forming member comprises a forked post or standard 18 journaled on a vertical axis in bearings 19 in the frame over the channel in the sheet and a wheel 20 journaled on a horizontal axis in the fork (at the lower 85 end) of the post. When this member is turned on its vertical axis one way or the other to an oblique position the fold-forming portion proper will, as an incident of the advance of the sheet, cause the latter 90 to shaft relatively laterally in a direction 100 105 110

opposite to that in which the leading edge of said fold-forming portion proper is thus displaced, being the result of said portion seeking to follow a path along the surface 5 of the sheet which is correspondingly oblique. We find the desired action in this way is best attained if the said portion of the fold-forming member takes the form of a rotary traction device or wheel, as 20, 10 which then on account of its engaging the sheet by a rolling as distinguished from sliding contact eliminates considerable slippage of the fabric with respect to it and makes the fold-forming member act more efficiently 15 in its function as a guide or director for the sheet.

Of course the turning of the fold-forming member or rudder can be controlled in any way so as to guide or direct the sheet and hence the line of fold. But we prefer to control said member automatically, as by the means shown diagrammatically in Fig. 2 where over each edge of the sheet is a pair of normally spaced elastic circuit closing 25 blades 21 in an electric circuit 22 containing a solenoid 23, the two blades being normally insulated from each other by a block of insulation 21^a (Fig. 1) from which they project and the two solenoids being alined and 30 (here) having a common core 24 and the two circuits (here) including a common source of energy 25. The solenoids are wound to act in opposite directions on the core, which is connected pivotally to an arm 35 26 projecting laterally from the fold-forming member. When the sheet shifts laterally one way or the other out of its predetermined course its then (laterally) leading edge by pressure on one of the circuit closers 40 in the adjoining pair forces it against the other and by closing the circuit and energizing the corresponding solenoid effects a compensatory turning of said member.

If different widths of sheets have to be 45 treated in the same machine there should be provision for changing the position of either the guide 1 or the fold-forming member vertically one relatively to the other. This is afforded in the present instance by the inclined set of bearings 7 for the guide.

The term "folding" as herein used con-

templates any condition of the sheet in which doubling would result, whether or not the fold formed is more or less sharply defined and whether or not the portions of 55 the sheet on opposite sides of the line of fold are in more or less substantially parallel planes.

It is desirable to provide the wheel with a tread adapted to prevent slippage, and for 60 this purpose we have equipped the wheel with a rubber tire.

Having thus fully described our invention, what we claim is:

1. A machine for folding a flexible sheet 65 while advancing the sheet edgewise including, with supporting means and coacting means therein for maintaining the sheet taut while being advanced, one of said coacting means acting to maintain the sheet spread 70 to substantially its initial width and the other acting to maintain the sheet doubled with the apex of the doubling projecting from a plane coincident with the spread portion of the sheet, a fold-forming rudder 75 revoluble in the supporting means back and forth on an axis penetrating said plane and having guiding contact with the sheet within its doubled portion.

2. A machine for folding a flexible sheet 80 while advancing the sheet edgewise including, with supporting means and coacting means therein for maintaining the sheet taut while being advanced, one of said coacting means acting to maintain the sheet spread 85 to substantially its initial width and the other acting to maintain the sheet doubled with the apex of the doubling projecting from a plane coincident with the spread portion of the sheet, a fold-forming rudder 90 including a support revoluble in the supporting means back and forth on an axis penetrating said plane and a wheel revoluble in the support on an axis transverse of the first-named axis and having rolling guiding 95 contact with the sheet within its doubled portion.

In testimony whereof we affix our signatures.

JAMES COOK.
PERCY COOK.
